CLAIM

The ornamental design for a mechanics creeper, as shown and described.

DESCRIPTION

FIG. 1 is a top perspective view of a mechanics creeper; FIG. 2 is a bottom perspective view of the mechanics creeper illustrated in FIG. 1;

FIG. 3 is a top view of the mechanics creeper illustrated in FIG. 1;

FIG. 4 is a bottom view of the mechanics creeper illustrated in FIG. 1;

FIG. 5 is a front view of the mechanics creeper illustrated in FIG. 1;

FIG. 6 is a rear view of the mechanics creeper illustrated in FIG. 1;

FIG. 7 is a left side view of the mechanics creeper illustrated in FIG. 1; and,

FIG. 8 is a right side view of the mechanics creeper illustrated in FIG. 1.

The dash-dash broken lines are included for the purpose of illustrating portions of the mechanics creeper that form no part of the claimed design. The dot-dash broken lines define the bounds of the claimed design and form no part thereof.

1 Claim, 6 Drawing Sheets
